UNITED STATES PATENT OFFICE.

JOHN P. GAREY, OF ELMIRA HEIGHTS, NEW YORK.

SPINNING FRAME AND THE LIKE.

Application filed April 28, 1921. Serial No. 465,236.

To all whom it may concern:

Be it known that I, JOHN P. GAREY, a citizen of the United States, residing at Elmira Heights, county of Chemung, and State of New York, have invented certain new and useful Improvements in Spinning Frames and the like.

My invention relates to spinning frames and the like and the object thereof is to provide simple and efficient means for stopping the feeding of rovings through the drawing rolls after the thread or yarn has been broken. The main object of my invention is to provide simple and reliable means for said purpose, the advantages in the construction and mode of operation of which will be apparent from the description hereinafter given.

In the drawings Fig. 1 is a vertical section through a portion of the spinning frame embodying my invention; Fig. 2 a plan view thereof; Fig. 3 an elevation on a larger scale illustrating my stop means and showing a portion thereof broken away; Fig. 4 an enlarged view of certain parts shown in Fig. 1; Fig. 5 a section on the line 5—5 of Fig. 3 and Fig. 6 a detailed view of a portion of a stop block and its operating arm. The spinning frame may be and is shown as of the ordinary type and comprising suitable frame members including a board or table 10 on which are arranged a large number of spinning units in the usual manner. The spinning mechanism proper includes a spindle 11 rotated by suitable mechanism (not shown) on which is mounted a spool 12 to receive the thread or yarn, a ring board 13 constructed and arranged to be reciprocated vertically in order to carry the ring 14 and traveler 15 thereon longitudinally of the spool during the winding operation.

The usual drawing rolls are employed, the same comprising three pairs of rolls 16, 17 and 18 revolved at progressively increasing speeds so that the rovings are drawn or lengthened by the relative movement of the fibres between successive pairs of rolls. A scavenger roll 19 is also employed to cooperate with the rolls 18. Supply bobbins 20, of which there are one or more for each set of drawing rolls, are mounted behind these rolls in position to feed the rovings thereon to the bite of the rolls.

The rovings 21 and 22 from the supply bobbins are carried through a trumpet guide 23 to the first pair of drawing rolls 16,

thence through the rolls 17 and 18 to the eye or guide 24 which is arranged in the axis of rotation of the spindle 11 and from which the thread is carried through the traveler 15 and thence to the spool 12. The guide 23 is mounted upon the usual reciprocating slide bar 25 which extends longitudinally of the frame and is common to all of the sets of drawing rolls, such slide being reciprocated by suitable mechanism, not shown. The horizontal bar 26 performs its usual functions of supporting the bearings of the drawing rolls.

Except for the specific form and mounting of the guide 24 hereinafter described in detail, the mechanism as thus far set forth is that which is common to most spinning machinery and therefore need not be further described.

Referring to my stop mechanism, the same comprises means for gripping the rovings after one or more of them or the thread or yarn has been broken, which mechanism is operated by controlling means whose action is dependent upon the continuity of the thread in such guide.

My stop mechanism is located between the bobbins and the drawing rolls and is supported by the bar 26.

As herein shown the stop mechanism comprises a block 27 which has a recess 28 whereby such block is fitted over the bar 26 and removably and adjustably secured thereto in suitable manner as by means of the set screw 29 passing through one side of the block and bearing against the bar 26. A plate 30 is secured to the block in suitable manner as by means of the screw 31, such separate construction being preferred although the block and plate might be made integral. This plate terminates at its upper end in a rearwardly extending flange 32 which acts as a protective covering. A flat bar or plate 33 extends parallel to the plate 30 and is attached thereto by means of the screw 31 and pins 34 passing through the two plates. This plate 33 is provided with guides 35 for the rovings, two such guides being provided on this plate inasmuch as the stop means being described is capable of accommodating two spinning units.

Between the two plates 30 and 33 and on the pins 34 there are pivoted two swinging weighted members or blocks 36 which are provided on their outer sides (which are lowermost when the blocks are operated)

with projecting strips or plates 37 whose outer ends are inclined inwardly for the purpose of catching and gripping the roving and stopping the feed thereof to the rolls. These 5 plates are in the form of teeth with a narrow opening 38 between them and the construction and arrangement are such that these teeth will be swung adjacent the inner side of the plate 33 and across the opening of 10 the guide 35. The inclined ends of these teeth engage the roving and the same is gripped in said opening 38 and against the inner side of the plate 33, thereby preventing any further drawing of the yarn from 15 the bobbins. The movement of the stop block 36 is limited in both extreme positions by the stop pin 39 which will bear against the top edge of the plate 33.

These blocks 36 are controlled in their operation by certain trigger mechanism dependent upon the position of the guide 24, which is in turn dependent upon the continuity of the thread or yarn. Referring to the controlling means, the same carries 25 at its forward end the guide 24 and at its rearward upward end a device cooperating with the lower end of an arm 40 which is pivoted at its upper end in a slot 41 in the lower end of the stop block, there being of 30 course two of these arms 40, one for each block of the structure above described. Each arm 40 is preferably of the construction shown, particularly with respect to the provision of a shoulder 42 thereon cooperating with the pin 43 for imparting to the block 36 its movement in one direction. Each arm carries at its lower end an adjustable trigger 44 terminating in a curved trigger proper indicated at 45 whose angularity is adjustable with respect to its 35 arm 44 and which latter arm is itself adjustable by reason of being attached to the arm 40 by the screw 46, as detailed in Figs. 3 and 5.

Referring to the details of the controlling means, the guide 24 is adjustably connected by the sleeve 47 and set screws 48 to a rod 49 which is pivotally connected at 50 in a bracket or support 51 mounted on the table 10. This rod 49 carries at its rearward end a weight 52 adjustably secured thereon and such rod also passes through and is secured to a horizontal cylinder 53 which in turn is provided with a vertical rod 54 carrying a cylinder 55. The cylinder 55 is provided at its upper end with a rod 56 curved at its upper end and adapted to cooperate with the trigger 45.

When the parts are in the normal position shown in Fig. 1 the stop blocks 36 are 60 in their normal position such as illustrated by the left hand one in Fig. 3 at which time such blocks are overbalanced inwardly and stopped in such position by contact of pin 39 with plate 33. However, if the yarn or

thread should break or the normal and proper spinning condition should be interrupted, the guide 24 will move upwardly, it being understood that the controlling means are adjusted so as to be in substantial balance or in equilibrium or preferably slightly overbalanced backwardly so that when the tension has released from the guide 24 the latter will move upwardly as stated. As a result the rod 56 will contact the trigger 45 and move the same inwardly thereby swinging its stop block 36 downwardly to a position where the same will be overbalanced whereupon such block will drop instantly and rapidly upon the yarn 75 passing through the guide 35 thereby clamping the roving in the manner as hereinbefore described. The pull of the drawing rolls will then break the fibre of the roving and feed from the roving bobbins ceases so that there can be no injurious accumulation 80 of roving on the drawing or scavenger rolls. The operator thereupon restores the stop block to normal position and rethreads the unit. 90

I claim:

1. In combination with the drawing rolls of a spinning frame or the like, and with the bobbin, a movable thread guide located between the rolls and the bobbin, a stop device for the roving comprising a plate having a guide opening for the roving, a clamping member pivoted at one end adjacent such opening and movable thereacross to catch and bind the broken roving thereat, and means connected with such thread guide and dependent upon the normal working position thereof for controlling the action of such clamping member. 95

2. In combination with the drawing rolls of a spinning frame or the like, and with the bobbin, a movable thread guide located between the rolls and the bobbin, a stop device for the roving comprising a plate having a guide opening for the roving, a clamping member pivoted at one end adjacent such opening and having a tapering slot at its other end to catch and bind the broken roving, such slot and member being so constructed and arranged that the mouth of the slot is substantially coincident with the guide opening in the initial movement of such member in order to engage the roving and that the remainder of the slot has a path of movement at one side of such opening, and means connected with such thread guide and dependent upon the normal working position thereof for controlling the action of such clamping member. 110

3. In combination with the drawing rolls of a spinning frame or the like, and with the bobbin, a movable thread guide located between the rolls and the bobbin, a stop device for the roving comprising a plate having a guide opening for the roving, a clamp- 125

ing member comprising a body portion and two laterally directed plates secured thereto and having inwardly tapered outer ends and separated slightly to form a tapering slot, said body portion being pivoted at one end in such position that said plates and slot are movable across the guide opening, and means connected with such thread guide and dependent upon the normal working position thereof for controlling the action of such clamping member.

4. In combination with the drawing rolls of a spinning frame or the like, a stop device for the roving comprising a plate having a guide for the roving, a member pivoted adjacent such guide and movable across the guide opening to catch and bind the roving thereat, and means dependent upon the normal condition of the roving or thread for controlling the action of said member, said means comprising a movable guide eye for the thread, lever connections operated thereby, and a lever pivoted on said member and operated by said lever connections.

25 5. In combination with the drawing rolls of a spinning frame or the like, a stop device for the roving comprising a plate having a guide for the roving, a member pivoted adjacent such guide and movable across the guide opening to catch and bind the roving thereat, and means dependent upon the normal condition of the roving or thread for controlling the action of said member, said means comprising a movable guide eye for the thread, lever connections operated thereby, and a lever pivoted on said member and having an adjustable arm operated by said lever connections.

40 6. In combination with the drawing rolls of a spinning frame or the like, a stop device movable from a normal position to an operative position to catch the roving when the continuity of the same or the thread is interrupted, and a movable element adapted in one direction of movement to trip the device and in the other direction of movement to slip thereby to a position ready for tripping the same.

50 7. In combination with the drawing rolls of a spinning frame or the like, a stop device movable from a normal position to an operative position to catch the roving when the continuity of the same or the thread is interrupted, a trigger arm connected with said device and a movable element adapted in one direction of movement to slip idly by said arm and in the other direction of movement to trip said arm and device.

60 8. In combination with the drawing rolls of a spinning frame or the like, a stop de-

vice movable from a normal position to an operative position to catch the roving when the continuity of the same or the thread is interrupted, a trigger arm pivotally connected with said device, and a movable element adapted in one direction of movement to swing said arm independently of said device and in the other direction of movement to swing said arm and device and thereby cause the latter to move to operative position.

9. In combination with the drawing rolls of a spinning frame or the like, a stop device for the roving comprising a plate having a guide for the roving, a second plate parallel to the first plate, a member pivoted between the two plates and movable across the opening of said guide to catch the roving thereat, and means dependent upon the normal condition of the roving or thread for controlling the action of said member, and a protecting means for said movable member.

20 10. In combination with the drawing rolls of a spinning frame or the like, a stop device for the roving comprising a plate having a guide for the roving, a second plate parallel to the first plate, a member pivoted between the two plates and movable across the opening of said guide to catch the roving thereat, and means dependent upon the normal condition of the roving or thread for controlling the action of said member, said second plate having a flange projecting over said pivoted member to protect the same.

35 11. In combination with the drawing rolls and the spool of a spinning frame or the like, a stop device for the roving, operating means for actuating said device, and means controlled by the condition of the thread between the rolls and the spool for holding said operating means out of cooperation with said device, said operating means and said device being independent except when such operating means are themselves operated by said controlling means.

45 12. In combination with the drawing rolls and the spool of a spinning frame or the like, a pivoted stop device which is set to operate upon and grip the roving, operating means for actuating said device but normally held out of cooperation therewith, and control means including a member which is located between the rolls and the spool and against which the continuous thread bears and adapted to bring the operating means into cooperation with said device and actuate the latter.

JOHN P. GAREY.
